C. A. Snow & Co.

UNITED STATES PATENT OFFICE.

HENRY D. WOODBRIDGE, OF NEWARK, OHIO.

BAG-HOLDER.

SPECIFICATION forming part of Letters Patent No. 433,114, dated July 29, 1890.

Application filed March 18, 1890. Serial No. 344,385. (No model.)

To all whom it may concern:

Be it known that I, HENRY D. WOODBRIDGE, a citizen of the United States, residing at Newark, in the county of Licking and State 5 of Ohio, have invented a new and useful Bag-Holder, of which the following is a specification.

This invention has relation to devices for supporting in a removable position paper 10 bags for use in retail stores employing such wrappers; and among the objects of the invention is to provide a cheap and simple device for yieldingly supporting a series of bags adapted to be successively withdrawn as required.

With the above objects in view the invention consists in certain features of construction hereinafter specified, and particularly pointed out in the claims.

Referring to the drawings, Figure 1 is a perspective of a holder constructed in accordance with my invention. Fig. 2 is a central vertical section, a series of bags being mounted in position.

Like numerals of reference indicate like parts in all the figures of the drawings.

In practicing the invention the holder is constructed in a single piece of spring-wire, and the details of construction are as follows: The blank of wire of suitable length is first doubled upon itself or bent at its center upon a mandrel to form a loop or eye 1, after which the two terminals are diverged, as at 2, and bent at an angle to the eye 1, forming a bearing portion 3. After diverging for a short distance, the two terminals are bent rearwardly to form a series of coils 4, said coils being formed upon a suitable mandrel or in other desired manner. After forming the coils 4

the terminals extend upward a short distance, and are laterally bent to form eyes 5, through which are inserted securing-screws 6, whereby the holder may be rigidly connected with any fixed object. Beyond the eye 5 the terminal extends upward for a short distance,

and is then bent laterally at each side of the holding portion 2, as at 7, and are bent to the

front to form bag-embracing arms 8, the ends of which are bent to form eyes 9.

The package of bags is introduced into the 50 holder by inserting the finger in the eye 1 and drawing said eye and the spring-holding portion 2 to the front, and after the bags have been inserted between the bag-embracing arms 8, and so that their lower ends rest 55 upon those portions of the terminals at each side of the spring-coils 4, the spring-holding portions release and serve to snugly press the bags in position. The embracing-arms 8 may be arranged at varying distances apart, so as 60 to accommodate bags of various capacities and hold the bags in proper alignment, and the entire structure also relatively increased in size. In placing the bags in the holder, the package of bags is inverted, so that their 65 doubled ends adapt them to be more readily grasped by the operator for withdrawal, and also, their closed ends being up, the entrance of dust within the bags is obviated.

Having described my invention and its operation, what I claim is—

1. The herein-described bag-holder, formed of a single piece of spring-wire bent at its center to form the eye 1, and having its terminals diverged at 2, thence rearwardly coiled at 4, 75 upwardly and outwardly bent to form screw-receiving eyes 5, horizontally bent at 7, and forwardly bent, as at 8, to form embracing-arms, substantially as specified.

2. The herein-described bag-holder, formed 80 of a single piece of spring-wire bent upon itself at its center and having its terminals downwardly-disposed and converged, rearwardly bent to form supports, upwardly bent and provided with screw-receiving eyes, and 85 terminating in forwardly-disposed embracing-arms, substantially as specified.

In testimony that I claim the foregoing as my own I have hereto affixed my signature in presence of two witnesses.

HENRY D. WOODBRIDGE.
